UNITED STATES PATENT OFFICE.

JOHN M. YOUNG, OF SAN FRANCISCO, CALIFORNIA, ASSIGNOR TO AMERICAN CAN COMPANY, A CORPORATION OF NEW JERSEY.

CAN-SYRUPING APPARATUS.

1,069,838.

Specification of Letters Patent. Patented Aug. 12, 1913.

Application filed January 30, 1911. Serial No. 605,563.

To all whom it may concern:

Be it known that I, JOHN M. YOUNG, a citizen of the United States, residing in the city and county of San Francisco and State of California, have invented certain new and useful Improvements in Can-Syruping Apparatus, of which the following is a specification.

The hereinabove described syruping apparatus is designed for use in connection with fruit canning factories generally for supplying the filled cans or packages with the syrup usually placed therein, although its use is not restricted to the syruping of filled cans or packages; the object of the invention being the production of a simple, effective, durable, and automatic machine for the desired purposes.

The cans or packages to be filled with syrup or liquid are automatically delivered to and removed from the filling orifices of the machine, the action of the valve mechanism controlling the flow of the syrup being automatically regulated by a can to be filled, and automatically closed on the filled can reaching a given position within the sphere of the rotatable syrup holding reservoir, the construction of working parts of the apparatus being such that the syrup controlling valves are not opened during the operation of the machine unless a can to be filled is delivered into the machine for actuating the means governing the unseating movement of the valve controlling the opening of the syrup outlets.

The apparatus comprises essentially a rotatable syrup holding reservoir, mechanism for imparting rotation thereto; a plurality of independently controlled syrup outlets in the reservoir, a plurality of independently vertically movable valves governing said outlets, devices for receiving and successively seating the cans against the valved controlled outlets, and means actuated by the inward feed of the cans for controlling the unseating of the valves to open the syrup outlets.

To comprehend the invention, reference should be had to the accompanying sheets of drawings, wherein—

Figure 1 is a sectional elevation view taken on line $x-x$, Fig. 2 of the drawings, disclosing the relative arrangement of the rotatable syrup reservoir, the valved syrup outlets, the valves for controlling the out-

lets, the vertically movable can chucks, the means for raising and lowering the said chucks, the rotatable can holder, the mechanism for imparting rotation to the supporting shaft and the parts sustained thereby, 60 and the means for raising and lowering the stems of the valves, one of the cans to be filled being indicated in lowered position, and the other lifted its full distance and the valve for the controlling syrup outlet for 65 said raised can as unseated. Fig. 2 is a top plan view of the syruping apparatus, the syrup reservoir being partly broken away illustrating the can carrier, the can holder, the feed and discharge runways for the cans, 70 the cam ring for raising and lowering the stems of the controlling valves, the inclined swinging section of the cam track, and the cam lever actuated by the movement of the cans for throwing inwardly the said swinging section of the cam track. Fig. 3 is a broken detail sectional view of the syrup reservoir and the can carrier, illustrating 75 one of the can chucks with a filled can seated thereon, one of the syrup outlet nozzles with its valve seated therein and the perforated disk or diaphragm covering the outlet nozzle, the filled can being illustrated in lowered position. Fig. 4 is a similar view 80 illustrating the filled can in lifted position and the controlling valve for the outlet nozzle raised from its seat. Fig. 5 is a broken detail elevation of the cam ring which actuates the controlling valves, disclosing the 85 swinging upwardly inclined section thereof. Fig. 6 is a horizontal sectional plan view 90 taken through the machine immediately above the rotatable can holder, illustrating the action of a can against the inclined cam lever for throwing the swinging section of the double inclined cam track, the segmental wall for holding a can within the can holder until clamped to the syrup reservoir, and the feed and discharge runways for the cans. Fig. 7 is a detail elevation of the cam lever 95 and the rotatable rod for operating the inclined swinging section of the cam ring.

In the drawings, the numeral 1 is used to indicate any suitable form of a supporting frame capable of sustaining the other parts 100 of the apparatus, and 2 is a driven shaft centrally extended within the frame and working in step bearings 3 and 3' of the top and bottom frame plates 4 and 4', which shaft is adjustable vertically by means of 110

the end adjusting screws 4² extended within the step bearings 4 and 4', the shaft 2 working on the bearing balls 4³ within said bearings. By this arrangement the shaft 2 may be raised and lowered to adjust the herein-after described syrup reservoir to position the same to cans of varying heights. The said vertically extended shaft 2 is driven by a pinion 5 on the transverse drive shaft 5' meshing with a gear 6 secured to the shaft 2, Fig. 1 of the drawings.

To the shaft 2 is keyed a rotatable table 7, which is provided with a plurality of circumferentially disposed seats 7' within which rest the vertically movable can chucks 8, each being provided with a depending stem or lift rod 8' working through guide brackets 9 depending from the rotatable table 7. To the lower end of each lift rod 8' is secured a roller 10, which rides on the fixed cam ring or double inclined trackway 10', secured to the base plate 4'.

A distance above the table 7 there is secured to the driven shaft 2 a turret provided with a plurality of can holders for receiving and holding the cans or packages to be filled. In the present case the said turret is in the form of a spider 11, to which is attached a plurality of can holders 12, which are designed to partly embrace the cans or packages 12' as delivered into the machine for receiving syrup, the cans or packages being held within said holders until clamped to the syrup reservoir by means of a segmental guard rail 13. The said can holders 12 are adjustably connected to the arms of the spider 11 and so arranged relatively to the carrier table 7 as to stand in vertical alinement with the can chucks 8, so that when a can or package 12' is within a holder, the same will be properly positioned on one of the vertically movable can chucks 8. These can holders constitute a portion of the spider 11 the arms of which are connected by the circular wall 13', hence the whole may be treated as a turret provided with a plurality of peripheral can holders. The turret is secured to the central shaft by being keyed or otherwise attached to the hub 14 of a disk 14' keyed to the said central shaft, to which disk is secured in any suitable manner a reservoir 15 for the syrup or liquid to be delivered into the cans or packages 12'. In the bottom of the reservoir 15 is formed a plurality of circumferentially disposed outlet openings, which register with corresponding outlet openings in the disk 14', from which depend a series of nozzles 16.

To prevent leakage of the syrup there is interposed a packing ring 16' between the bottom of the reservoir and the upper face of the disk 14', and a similar packing ring 17 is interposed between the nozzles 16 and the under face of the said disk 14'. Sur-

rounding each outlet opening and within the reservoir 15 is a valve guide 18, within which works a valve 18', when raised from off its seat 19, each of said valves carrying a packing ring 19' for making a tight joint when lowered onto its seat.

From each valve 18' upwardly extends a valve stem 20, which is projected above the open reservoir 15, working through guides 15' of spider 15² fixed to the central shaft 2, and to the upper end of each stem is secured an outwardly extended bracket 20', carrying a roll 21. These rolls work on the upper surface of a double inclined cam ring 22, held within the frame 1 by the brackets 22² depending from the top frame plate 4, Fig. 1 of the drawings. The upwardly inclined portion of the said cam ring 22 is in the form of an outwardly swinging gate section 22', Fig. 5 of the drawings, the inner end of which is secured to an arm 23, pivoted to the forward end of the upper or raised section a', of the cam ring 22, and the outer end of the arm 23 is connected by a link 24, Fig. 2 of the drawings, to a downwardly extended rock rod 24'. This rod is connected at its lower end to an inwardly extended cam lever 25, which lever is projected inwardly to lie within the path of the cans or packages 12' as delivered into the machine to be filled with syrup. From the rock rod 24' projects a stud 25', and connection is made between the same and the frame of the machine by means of the spring 26, the tension of which spring is sufficient to hold the rod 24' in such a position as to normally maintain the swinging section 22' of the cam ring 22 open or swung outwardly. When thus opened the roll 21 of the valve stems 20 as carried off the lower section a of the cam ring 22 instead of passing or continuing onto the upper or raised section a' thereof will pass beneath or under the same, in which case the valve stem 20 is not raised and the valve 18' remains seated. The roll 21 enters onto the upper surface of the lowered section a of the cam ring 22 as it is carried beneath the downwardly inclined section 27 of the said cam ring, which section is hinged to the terminal point of the raised section a' of the cam ring for upward movement and is raised by the pressure of the roll 21 thereagainst to permit of the same entering onto the upper surface of the lowered section of the cam ring.

The filled cans or packages 12' are delivered onto the rotating carrier 7 from the feed runway 28, being carried thereto by the endless conveyor 28', and are removed from the machine onto the said conveyor by means of the discharge runway 29. As the foremost can of the series of cans is moved into one of the can holders of the turret 11, the same will rest on one of the can chucks 8 and in line with and below one of the out-

jet nozzles 16 of the disk 14', and will be held in its holder by the segmental wall 13. During the rotary travel of the carrier 7, the roll 10 of the depending stem 8' of the can chuck 8 rides upon the upwardly inclined section of the cam ring 10 gradually raising the same and lifting the can chuck 8 with the filled can 12' seated thereon until its open end is firmly pressed against the packing ring 16² surrounding the nozzles 16 for the making of a tight joint. During this rotary travel of the filled can 12' the same bears against the free end of the cam lever 25 and forces the same outwardly, which turns the rock rod 24' and throws the lever 23 through its link connection 24 to shift inwardly the downwardly inclined swinging section 22' of the cam ring 22, over which rides the roll 21 of the valve stem 20, for gradually raising the said stem to lift and unseat the valve 18', permitting the syrup to flow from the reservoir 15 through the outlet nozzle 16 into the clamped can or package 12, the said valve remaining open until the roll 21 enters onto the hinged downwardly inclined portion or section 27 of the cam ring 22, which causes a gradual lowering of the valve stem and a seating of the valve carried thereby to cut off the outflow of syrup from the reservoir, after which the roll 10 of the can chuck stem 8' rides upon the downwardly inclined portion or section 6 of the cam ring 10', causing the can chuck 8 to gradually lower and place the filled can within the sphere of the discharge runway 29 for guiding the same onto the conveyor 28.

Inasmuch as the loose fruit within the can or package 12' to receive the syrup usually projects beyond the open end of the can or package, Fig. 3 of the drawings, it is required that the said fruit be compressed within the can prior to the syrup being admitted thereto. For this purpose and to prevent the fruit being forced from within the open-ended can 12' as the syrup is admitted therein, there is provided a perforated diaphragm 29' for each outlet nozzle 16, the screw-threaded flange 30 of which screws onto the threaded end 30' of the said nozzles. Under this construction, as the filled can 12' is moved upwardly against the packing seat 16², the nozzle 16 with its secured perforated diaphragm enters the open end of the said can, the diaphragm 29' bearing onto the loose fruit and compressing the same within the can and holding the fruit against upward movement as the syrup is forced into the said can, Fig. 4 of the drawings.

As the open end of the can 12' is held firmly against the packing seat 16² by the chuck head 8 when raised its full distance, the air expelled from the can during the filling of syrup therein escapes through the

perforated diaphragm 29' into the open syrup reservoir and escapes through the body of syrup contained therein, the air outlet vents commonly employed in connection with can-syruping machines being thus dispensed with.

By the employment of the described apparatus the cans are successively received and filled with syrup, and as the action of the working parts is entirely automatic the cans are perfectly and expeditiously filled with syrup, each can being filled to its full capacity and this irrespective as to the quantity of fruit therein; in other words, a predetermined quantity of syrup is not supplied to each can, but each can is completely filled with syrup without regard to the quantity supplied to any other can.

As the cans delivered into the machine control the closing action of the swinging section 22' of the cam 22, which section normally stands open, the valves controlling the syrup outlets are not unseated unless cans are being delivered into the machine, hence if for any reason there is a stoppage in the feed of the cans requiring syruping, it is not required to stop the working of the syruping machine.

It will be understood that the described rotating features of the syruping machine work in unison, each being driven from the central drive shaft 2, and that the working of each vertically movable can chuck 8 is so timed that the same is raised to clamp a can to its filling nozzle just prior to the unseating of the controlling valve, therefor, and lowered to release the clamped can after the said controlling valve has been seated, the said valve remaining open for approximately one-half the rotation of the syrup containing reservoir in order to give ample time for the filling of the can with syrup.

By actuating the regulating or adjusting screws 4² the central shaft 2 may be raised and lowered to adjust the syrup holding reservoir 15 toward and from the table 7 to vary the position thereof relative to the stroke of the can chucks 8, in order to adjust the machine to the working requirements for cans of varying lengths, and by shifting the position of the adjustable can holders 12 horizontally with respect to the sustaining turret or spider 11, which is accomplished by loosening the set screw 12^a, the said holders are regulated relative to the segmental wall 13 to receive filled cans of varying diameter.

I am aware that various modifications may be made in the construction of the working parts of the herein described apparatus without departing from the involved invention, which resides in rotatable means for successively receiving cans to be filled with syrup, automatically clamping the same in position, filling the same with syrup dur-

ing the rotary travel of the clamping and sustaining mechanism, and successively discharging the filled cans from the syruping apparatus, and in the means thrown into action by the movement of a received can for shifting the devices for regulating the unseating of the valves controlling the outflow of syrup from the revolving syrup holding reservoir, whereby the machine is of such a 10 construction as to cover the idea of "no can, no syrup."

Having thus described the invention what is claimed as new and desired to protect by Letters Patent is—

- 15 1. In an apparatus for the described purpose, the combination with the frame thereof, of a cam ring secured thereto, a rotatable syrup reservoir provided with a plurality of circumferentially disposed syrup outlets, a valve in each outlet, a stem extended from each valve carrying a roll for engagement with the mentioned cam ring, a swinging section in said cam ring for controlling the opening movement of the valves for the 20 syrup outlets, a rotatable can carrier located below the syrup reservoir, a plurality of can chucks carried thereby; devices for successively raising and lowering the said chucks toward and from the valved outlets 25 of the reservoir during the rotary movement thereof, means for successively delivering onto the can chucks cans to be filled, and a device in the path of a raised can for throwing the swinging section of the cam ring to 30 cause the unseating of the valve controlling the flow of syrup into such raised can.
2. In an apparatus for the described purpose, the combination with a rotatable syrup holding reservoir provided with a plurality 35 of circumferentially disposed outlets, a vertically movable valve for each outlet provided with a stem projected above the reservoir, a cam ring for actuating said stems to raise and lower the valves, a swinging section in said cam ring for controlling the unseating of the valves, means for successively receiving and clamping cans to be filled to the said outlets of the reservoir prior to the

unseating of the valves thereof, and a device situated in the path of the clamped cans 50 and operated independently by each can for shifting the position of the swinging section of the cam ring to cause the raising of the valve stem and unseating of the valve carried thereby controlling the syrup outlet to 55 which such can is clamped.

3. In a device for the described purpose, the combination with a rotatable syrup reservoir provided with a plurality of circumferentially disposed valve controlled outlets, 60 a cam ring for actuating said valves, an inwardly swinging section in said cam ring for controlling the unseating of the valves of the outlets of the reservoir, devices for clamping cans to said outlets, and means 65 acted on by the clamped cans for throwing inwardly the swinging section of the cam ring.

4. In an apparatus for the described purpose, the combination with a supporting 70 frame, a rotatable reservoir provided with a plurality of circumferentially disposed valved outlets, a valve stem projecting from each valve of the said outlets, a cam ring secured to said frame for actuating said 75 valve stems, a swinging section in said cam ring, a vertically disposed spring held rock rod for shifting the swinging section of the cam ring, vertically movable clamping means for successively clamping cans to the 80 valved outlets of the reservoir, and a lever extended from the rock rod and projecting within the path of the clamped cans, said lever being acted on successively by the clamped cans to throw the swinging section 85 of the cam ring to control the unseating of the valve of an outlet with a can clamped thereto.

In testimony whereof I have signed my name to this specification in the presence of 90 two subscribing witnesses.

JOHN M. YOUNG.
